(57) **CLAIM**

The ornamental design for a shoe sole, as shown and described.

DESCRIPTION

The patent or application file contains at least one drawing executed in color. Copies of this patent or patent application publication with color drawing(s) will be provided by the Office upon request and payment of the necessary fee.

FIG. 1 is a bottom perspective view of a shoe sole in accordance with my new design; and,

FIG. 2 is a bottom plan view.

The broken lines shown in the drawings represent portions of the shoe sole and environmental structure in the form of a shoe outsole bottom that form no part of the claimed design. The surfaces devoid of photographic surface form no part of the claimed design. Color forms no part of the claimed design.
